SPRING EJECTED TOY VEHICLE

Charles T. Borchers, Shelbyville, Ind.

Application April 16, 1948, Serial No. 21,332

1 Claim. (Cl. 46—202)

1

This invention relates to toys, and particularly mechanical toys.

The primary object of the invention is to provide a mechanical toy in the form of a fire vehicle, together with a building representing the fire house, means being provided for ejecting the vehicle from the building, when the door has been opened to a predetermined position.

An important object of the invention is to provide mechanical means which may be set by the movement of the toy vehicle to its proper position within the building, so that by actuating the door, the ejecting mechanism will be released.

With the foregoing and other objects in view which will appear as the description proceeds, the invention consists of certain novel details of construction and combinations of parts, hereinafter more fully described and pointed out in the claim, it being understood that changes may be made in the construction and arrangement of parts without departing from the spirit of the invention as claimed.

Referring to the drawing

Figure 1 is a sectional view through a building illustrating a toy vehicle as positioned therein with the ejecting means in its set position, the view being taken on line 1—1 of Fig. 2.

Fig. 2 is a sectional view taken on line 2—2 of Fig. 1.

Fig. 3 is a sectional view taken on line 3—3 of Fig. 2, illustrating the tracks formed in the floor of the building.

Referring to the drawing in detail the building or toy fire house, is indicated generally by the reference character 5 and is provided with a floor 6 in which the tracks 7 are formed, the tracks being in the form of longitudinal grooves extending from the rear wall to the front of the building to accommodate the wheels of the fire vehicle forming a part of the toy, so that the vehicle when ejected from the building will move in a direct line.

The reference character 7' indicates the door of the building, which is hingedly connected to the building, by means of the hinges 8 which are arranged in spaced relation with the upper end of the door, as clearly shown by Fig. 1 of the drawing.

Mounted within the building, at a point adjacent to the rear wall thereof, is a tubular housing

9 in which the rod 10 operates, the rod 10 extending through an opening in one end of the tubular housing 9, where it is supplied with the bar 11 that is of a length to extend across a pair of tracks 7.

A coiled spring indicated by the numeral 12 is positioned around the rod 10 and has one of its ends bearing against the washer 13 that is held against the pin 14, the opposite end of the spring 12, bearing against the vertical housing 15 in which the latch 16 moves.

A notch is formed in the rod 10 and receives the end of the latch member 16, which is forced towards the rod 10, by means of the spring 17.

As clearly shown by Fig. 1 of the drawing, the rod 10 is of a length to extend through an opening in the rear wall of the building, where it is supplied with the finger piece 18 which may be gripped by the operator to pull the rod 10 rearwardly and set the device for operation.

Connected with the latch member 16, is the cable 19 which passes over the pulleys 20 and 21 mounted in brackets suspended from the roof of the building.

25 The reference character 22 indicates toy vehicles which have supporting wheels that are disposed within the tracks of the floor. When the vehicles are positioned within the building, the bar 11 is pulled to the position as shown by Fig. 1 of the drawing. The device is now set, since the latch member 16 will move into the notch of the rod 10, holding the rod 10 and bar 11 in their set positions.

It is obvious that when the door 7' is moved to its open position, the end 23 of the door which extends beyond the hinge 8, will contact with the cable 19 moving the cable to the dotted line position as shown by Fig. 1 of the drawing, tending to shorten the cable. This action results in

40 the cable being pulled which in turn pulls the latch member 16 to its releasing position. The rod 10 is now forced forwardly by the action of the coiled spring 12, which forces the toy vehicles through the open door of the building, simulating the movements of vehicles passing from the building under their own power.

45 From the foregoing it will be seen that due to the construction shown and described, I have provided a toy which is exceptionally amusing, and one which will be attractive to young people.

While I have shown and described mechanical motors in the form of coiled springs for ejecting the toy vehicles from the building, it is to be understood that various other types of spring motors, electric motors or the like may be used in shortening the cable to operate the latch and release the ejecting means, without departing from the spirit of the invention.

Having thus described the invention, what is claimed is:

In a mechanical toy, a toy building having a hinged door at the front thereof, and in which a toy vehicle is positioned, a horizontally disposed tubular housing mounted within the building at the rear thereof, a spring pressed rod extending into the building through the rear wall of the building, said rod passing through the tubular housing, a handle on one end of the spring pressed rod by means of which the rod is moved to its set position, a bar secured to the end of the rod extending into the building against which the toy vehicle is positioned, a spring pressed

10

latch engaging in a notch of the rod, normally holding the rod in its set position, a cable secured to the latch, said cable being connected to the door whereby movement of the door to its open position operates the latch releasing the spring pressed rod ejecting the vehicle through the open door.

CHARLES T. BORCHERS.
